CARL F. SCHULZ, OF BROOKLYN, NEW YORK.

CARBURETER.

1,010,184.

Specification of Letters Patent. Patented Nov. 28, 1911.

Application filed January 19, 1911. Serial No. 603,491.

To all whom it may concern:

Be it known that I, CARL F. SCHULZ, citizen of the United States, residing at Brooklyn, in the county of Kings and State of New York, have invented certain new and useful Improvements in Carbureters, of which the following is a specification.

This invention comprehends certain new and useful improvements in carbureters for internal combustion engines, and the invention has for its primary object an improved construction of device of this character embodying and possessing the characteristics of susceptibility of control and other advantageous features that are incidental to carbureters of the mechanical type, as well as the characteristics of simplicity and sensitiveness and other advantages of the automatically acting type of carbureter.

The invention also has for its object an improved carbureter embodying a pneumatically actuated air admission valve so arranged that when it is desired to have the valve moved toward open position under the influence of the suction of the engine, it is only necessary to admit atmospheric pressure on that side of the valve or piston which is not exposed to the vacuum created by the suction of the engine, and also so arranged that when it is desired to arrest or limit the movement of the valve or piston in any desired place, it is only necessary to cut off the atmospheric pressure or communication from the face of the valve or piston not exposed to the vacuum in the mixing chamber, the pressure being automatically balanced on both sides of the valve or piston by establishing communication between the mixing chamber and the face of the piston which is not exposed to said chamber.

The invention also has for its object an improved carbureter which may be practically termed a "throttleless carbureter" or one embodying only a pneumatic throttle, the air valve, throttle, and fuel valve all moving together, and means being provided, as above stated, whereby the movement of the air-admission valve may be arrested or limited in any desired position by the balancing of pressure on opposite sides of the piston which forms part of said admission valve.

A still further object of the invention is a carbureter embodying an automatic valve

adapted to regulate the pressure on the surface of the fuel, and designed to insure at all times the proper proportion of fuel and air under a varying vacuum. And the invention also aims to simplify and render more durable and efficient devices of this character so as to make them more useful and commercially desirable.

With these and other objects in view that will more fully appear as the description proceeds, the invention consists in certain constructions, arrangements and combinations of the parts that I shall hereinafter fully describe and claim.

For a full understanding of the invention, reference is to be had to the following description and accompanying drawing in which:

Figure 1 is a vertical sectional view of a carbureter embodying the improvements of my invention, parts being shown in side elevation and one part being partly broken out. Fig. 2 is a horizontal sectional view on the line 2-2 of Fig. 1; Fig. 3 is a detail sectional view of a pressure regulating valve hereinafter specifically referred to; Fig. 4 is a view illustrating a different form of said valve; and, Fig. 5 illustrates in detail a portion of the inspirator nozzle and its valve.

The casing of my improved automatic carbureter is provided with a float chamber 1 having a fuel inlet passage 2 leading thereto, an opening 1^a to the atmosphere, and an air inlet opening 3 designed to communicate with the interior of a downwardly projecting cylinder 4 forming part of the casing, 90 and a mixing chamber 5 which communicates with the interior of an upwardly projecting cylinder 6 forming the upper end of the casing.

The top 7 of the casing is formed with a 95 longitudinally disposed and preferably centrally located tubular bearing 8 in which a cylindrical sleeve 9 is mounted for longitudinal movement, the sleeve being formed at its upper end with a grooved collar 10 in which the forked arm of a bell-crank 100 controlling lever 11 is mounted, the other arm of said lever being connected in any desired way to some operative means (not shown) in convenient proximity to the operator.

A longitudinally fluted or ribbed stem 12 is mounted for longitudinal movement in the

circular bore of the sleeve 9, said stem being provided at its upper end with an annular shoulder 13 designed to engage or contact with the upper face 14 of the sleeve 9, so as to prevent atmospheric air from flowing into the sleeve 9 through the passages produced by the fluted formation of the stem 12.

A piston 15 is mounted to move longitudinally in the cylindrical portion 6 of the 10 casing, said piston, specifically considered in the present embodiment of the invention, being formed with a depressed head 16 whereby a chamber is always maintained within the cylinder 6 on that face of the 15 piston which is not exposed to the partial vacuum created in the mixing chamber 5 by the suction of the engine. The pressure-controlling stem 12 passes down entirely through the sleeve 9 and its surrounding 20 bearing 8 and freely down through a central opening formed for it in the head 16 of the piston 15, being provided with a valve seat 17 designed to open and close any desired number of ports 18 that are formed 25 in the head 16, said ports being designed to establish communication between the mixing chamber 5 and that face of the piston 15 which is not exposed to the suction created in said mixing chamber. Normally, the 30 valve seat 17 is held against the ports 18 by an expansion spring 19, as clearly illustrated in the drawing. The stem 12 is connected to or identical with the stem 20 of the fuel-controlling valve the lower end 35 of which works within the spray nozzle 21 which is located in the downwardly projecting cylindrical end 4 of the casing.

A port 22 leads from the air inlet opening 3 into the air inlet chamber 23 that is 40 embodied in the casing, said port being controlled by a port 24 which leads into a chamber 25 formed in the downwardly extending cylindrical lower end 26 of the piston 15, the lower end of this chamber communicating 45 directly with the interior of a tube 27 which depends from the main body portion of the piston 15 and the interior of which constitutes a fuel inspirating and mixing passage 28 leading directly into the 50 interior of the main body portion of the piston and from thence communicating directly with the mixing chamber 5. The piston 15 with its extensions constitutes in effect a pneumatic throttle and air-admission 55 valve combined and moves with and produces the movement of the fuel valve which operates in the spray nozzle 21. The parts are normally held in closed position by a spring 29 or its equivalent, although it 60 is to be understood that this is not indispensable, as other means may be provided for this purpose.

From as much of the description as has preceded, together with the accompanying 65 drawing, it will be understood that in the

practical operation of my improved carbureter, when the engine is started, the bell crank lever 11 is operated so as to move the sleeve 9 downwardly, separating the face or seat 14 of the sleeve the desired distance 70 from the shoulder or seat 13 of the pressure-controlling stem 12, and thereby permitting atmospheric air and pressure down through the sleeve to act on the upper side of the piston 15. Upon the admission of atmospheric 75 air to the upper side of the piston, the piston will naturally move downwardly, owing to the fact that a partial vacuum is created in the mixing chamber by the suction of the engine; and consequently, as the 80 piston moves down, the port or ports 24 will register with the port 22, so as to admit air into the air passage or chamber 25 and from thence into the mixing passage 28 in which the stem of the fuel-controlling valve 85 is mounted. It is manifest that the stem 12 will move down as the piston 15 moves down, and consequently, when the valve stem 12 has moved in the sleeve 9 sufficiently to effect the engagement of the seats 13 and 90 14, the atmospheric communication between the space within the cylinder 6 on the upper face or side of the piston 15, will be cut off, while the communication between the mixing chamber 5 and said space or chamber 95 on the upper side of the piston will be established through the ports 18 that are normally closed by the valve seat 17 of the stem 12. Hence the pressure on both sides of the piston will be balanced, the atmospheric 100 communication from the side of the piston not exposed to the vacuum in the mixing chamber will be shut off, and the opening movement of the piston will be arrested.

It will thus be seen that, broadly considered, I have provided a very simple carbureter in which, when it is desired to have the air-admission valve move toward open position under the influence of the suction of the engine, it is only necessary to admit 105 atmospheric pressure on that side of the piston which is not exposed to the vacuum created by the suction of the engine; and that when it is desired to arrest or limit the movement of the valve or piston in any desired place, it is only necessary to cut off the atmospheric communication from that side of the valve or piston which is not exposed to the partial vacuum in the mixing chamber, and to balance the pressure on both 110 sides of the piston as hereinbefore specified.

In addition to the features described in the foregoing part of the specification, my invention also embodies a valve 30 which is mounted in a pipe or other connection 115 between the mixing chamber 5 and the space above the gasoline or other hydro-carbon fuel in the float chamber 1. In a carbureter such as that here shown, it is evident that the vacuum will vary greatly in the mixing 120

chamber, as well as the velocity of the incoming air and fuel. It is well known that with an air and fuel mechanism maintained at an approximate constant ratio or opening between the two, an increase of velocity or vacuum will of itself change the proportion or ratio between the fuel and air, and the spring-pressed valve 30 is designed to automatically regulate the pressure on the surface of the liquid fuel, and to insure the proper proportion of fuel and air under a varying vacuum. It will be noted that the valve 30 is formed with a slot 32 substantially of inverted V-shape. With this construction of valve, it is evident that the pressure on the liquid fuel in the float chamber will drop with an increase of vacuum in the mixing chamber, as the valve 30 will rise. If it be desired to have the pressure on the fuel increase rather than decrease, it is only necessary to have the V-slot broadened out at the top, gradually decreasing, instead of increasing, communication between the mixing chamber and the float chamber as the vacuum increases in the former. This form of the regulating valve is illustrated in Fig. 4, where 30^a designates the valve and 32^a the slot thereof. It is of course to be understood that the increase of pressure on the fuel, if this be desired, is only relative. It can never become greater than atmospheric pressure.

By my invention, I eliminate every obstruction to the progress of the air and fuel, upon admission, to the engine, thereby insuring greater power, better carburation, and less condensation and loss of fuel in the mixing chamber.

While the accompanying drawing shows what I believe to be the preferred embodiment of my invention, it is to be understood that my invention is not limited thereto, as various changes may be made in the construction, arrangement and proportions of the parts without departing from the scope of the invention as defined in the appended claims.

What I claim is:

1. A carbureter embodying a fuel inlet valve and provided with an air inlet opening and a mixture outlet opening, an air admission valve arranged to admit air from the air inlet opening into the carbureter whereby it may pass to the mixture outlet opening, said valve being movable by suction toward open position, and pressure-controlling means arranged to balance the pressure of the suction on opposite sides of said valve, at predetermined positions thereof.

2. A carbureter embodying a fuel inlet valve and provided with an air inlet opening and a mixture outlet opening, an air-admission valve connected to the fuel valve and arranged to admit air into the carbureter from the air inlet opening whence it

may pass to the mixture outlet opening, and pressure-controlling means arranged to balance the pressure of the suction on opposite sides of said valve at predetermined points in the movement of the air-admission valve 70 toward open position.

3. A carbureter, embodying a fuel inlet valve, and provided with an air inlet opening and a mixture outlet opening, an air admission valve arranged to admit air into 75 the carbureter from the air inlet opening whence it may pass to the mixture outlet opening, one face of said air-admission valve being exposed to the suction in the mixture outlet opening, means for admitting atmospheric air to the opposite face of said valve whereby to permit the suction to move said valve toward the open position, and means, controllable at will, for automatically shutting off atmospheric pressure from such side 80 of the air-admission valve, and for balancing the pressure of the suction on both sides of such valve.

4. A carbureter embodying a fuel inlet valve and provided with an air inlet opening 90 and a mixture outlet opening, an air-admission valve operatively connected to the fuel inlet valve and having one of its sides exposed to the mixture outlet opening whereby to be acted on by the suction there- 95 in, means for admitting atmospheric air to the opposite side of said air-admission valve, and means for shutting off said atmospheric air and for opening communication between such side of the air-admission valve and the 100 side which is exposed to the mixture outlet opening.

5. A carbureter embodying a fuel inlet valve and provided with an air inlet opening and a mixture outlet opening, an air-admission valve embodying a piston provided with a passage surrounding the fuel inlet valve and a port leading to said passage and adapted to register with the air inlet opening, the passage leading to the mixture outlet opening, said piston having one side exposed to the suction in the mixture outlet opening, means, controllable at will for admitting atmospheric air to the opposite side of said piston, and means for automatically 105 shutting off said atmospheric air and for establishing communication between the opposite sides of the piston.

6. In a carbureter, the combination of a fuel inlet valve, a casing in which said valve is mounted, the casing being provided with an air inlet opening and a mixture outlet opening, an air-admission valve adapted to admit air into the casing from the air inlet opening whence it may pass to the mixture outlet opening said air-admission valve having one side exposed to the suction in the mixture outlet opening, adjustable means arranged to admit atmospheric air to the opposite side of said air-admission valve

whereby to permit said valve to move by suction toward open position to a predetermined point, and means for automatically shutting off the atmospheric air from such side of the air-admission valve and for opening such side to the suction in the mixture outlet opening when such point has been reached.

7. A carbureter, comprising a casing provided with an air inlet opening and a mixture outlet opening, a piston movable in said casing and provided with a head one side of which is exposed to the suction in the mixture outlet opening, the piston being provided with a port adapted to register with the air inlet opening to permit air to enter the casing and thence flow to the mixture outlet opening, a sleeve movable in said casing and adapted to be held in different adjusted positions therein, a pressure-controlling stem movable in said sleeve and adapted to control the admission of atmospheric air into the sleeve whence it may pass to that side of the piston head which is not exposed to the suction in the mixture outlet opening, the head being provided with ports and the stem being provided with a valve seat adapted to close said ports and spring-pressed toward closed position, and a fuel-controlling valve connected to said stem.

8. A carbureter, comprising a casing provided with an air inlet opening and a mixture outlet opening, a fuel-controlling valve mounted in said casing, a piston movable in said casing and provided with a head one side of which is exposed to the suction in the mixture outlet opening, a sleeve movable in one end of the casing, a stem movable longitudinally in said sleeve, the stem being adapted to control the passage of atmospheric air through the sleeve and to that side of the piston head which is not exposed to the suction in the mixture outlet opening, the head being formed with an opening extending therethrough and the stem being provided with a valve seat adapted to close said opening, the stem being arranged to move the fuel-controlling valve and the piston being provided with a port adapted to

register with the air inlet opening and with a passage surrounding the fuel-controlling valve and establishing communication between said port and the mixture outlet opening, and means for adjusting said sleeve to 55 different positions.

9. A carbureter, comprising a casing formed with an air inlet opening and a mixture outlet opening, a fuel-controlling valve mounted in said casing, the casing being provided in its top with a longitudinally disposed bearing, a sleeve mounted for a longitudinal movement in said bearing, the sleeve being provided with a collar, a controlling lever engaging said collar to move 60 the sleeve longitudinally, a longitudinally fluted stem mounted in the sleeve and movable longitudinally therein, the stem being operatively connected to the fuel-controlling valve and provided at its upper end with a 70 head adapted to abut against one end of the sleeve to shut off the access of atmospheric air to the interior of the sleeve and thence to that side of the piston which is not exposed to the suction in the mixture 75 outlet opening, the opposite side of the piston being so exposed and the piston being provided with an opening designed to establish communication between the opposite sides of said piston, and means carried by 80 the stem for automatically closing said opening upon the contact of the head of the stem with the upper end of the sleeve.

10. A carbureter provided with a float chamber and a mixture outlet opening, a 85 connection between the mixture outlet opening and the float chamber above the level of the liquid in the latter, and a valve mounted in said connection and formed with a tapering port arranged to automatically 90 vary the communication between the mixture outlet opening and the float chamber, whereby to regulate pressure on the surface of the fuel in the float chamber.

In testimony whereof, I affix my signature in presence of two witnesses.
